UNITED STATES PATENT OFFICE.

ELI M. LONG, OF GENEVA, NEW YORK, ASSIGNOR TO THE STANDARD OPTICAL COMPANY,
OF GENEVA, NEW YORK, A CORPORATION OF NEW YORK.

EDGE-GRINDING MACHINE FOR LENSES.

1,298,979.

Specification of Letters Patent.

Patented Apr. 1, 1919.

Original application filed June 2, 1916, Serial No. 101,282. Divided and this application filed March 18, 1918. Serial No. 223,040.

To all whom it may concern:

Be it known that I, ELI M. LONG, a citizen of the United States of America, and resident of Geneva, in the county of Ontario, in the State of New York, have invented new and useful Improvements in Edge-Grinding Machines for Lenses, of which the following, taken in connection with the accompanying drawings, is a full, 10 clear, and exact description.

This invention relates to certain improvements in edge-grinding machines for lenses, in which the rotary lens-holder is reciprocated axially across the face of a rotary 15 grindstone for reducing the lens to the desired form according to a predetermined pattern, as a division of my pending application, Ser. No. 101,282, filed June 2, 1916.

The main object is to increase the general 20 working efficiency of machines of this character by reciprocating the lens-holder across the face of the grinder through the medium of an oil pump and adjustable means for reversing the direction of flow of 25 the oil from the pump and varying the distance of travel of the carriage at will.

Other objects and uses relating to specific parts of the machine will be brought out in the following description.

30 In the drawings—

Figures 1 and 2 are, respectively, a top plan and a side elevation of an edge-grinding machine embodying the various features of my invention.

35 Figs. 3 and 4 are enlarged vertical sectional views taken, respectively, on lines 3—3 and 4—4, Fig. 1.

Fig. 5 is an enlarged vertical sectional view through the front portion of the machine taken on line 5—5, Fig. 1.

40 Figs. 6 and 7 are further enlarged horizontal sectional views taken in the planes of lines 6—6 and 7—7, Fig. 5.

Fig. 8 is an enlarged detail sectional view 45 taken on line 8—8, Fig. 2.

Main supporting frame.

As illustrated, the main supporting frame 50 consists of a substantially semi-circular trough-like shell or casing —1— adapted to be secured in a horizontal position to any available support for receiving and inclos-

ing the lower half of a rotary grindstone, presently described, and confining the waste resulting from the grinding operation, together with the drip of water used in moistening the periphery of the grindstone, the lower front side of the trough being provided with a cleanout opening —2— and a closure —3— therefor, as shown more clearly in Fig. 3.

A shield —4— is secured to the upper rear edge of the main frame —1— and constitutes a part thereof and incloses the upper rear portion of the grindstone for confining the waste within the environs of the underlying trough.

A waste-containing reservoir —5— is mounted upon the upper front end of the shield —4— directly over the grindstone and is provided with a suitable faucet —6— for supplying moisture to the periphery of the stone.

The front portion of the frame —1— is provided with an upwardly and forwardly inclined guidway —7— along and upon which is adjustable a movable section —8— for receiving and supporting a sliding carriage for the lens-holding frame and truing device, hereinafter described, the movable section —8— being held in its adjusted position by one or more clamping bolts —9—, Fig. 2.

Grinding device.

As illustrated, the grinding device consists of a rotary circular grindstone —10— adapted to revolve in the frame —1— and shield —4—, and for this purpose is mounted upon a rotary shaft —11— which is journaled in suitable bearings —12— on the upper edges of opposite sides of the frame —1— and is provided at one end with a pulley —13— adapted to be connected by a belt —14— to any available source of power, not shown, the grindstone being held against axial movement by suitable collars on the shaft at opposite sides of the grindstone.

Sliding carriage and operating means therefor.

The top of the adjustable section —8— of the main supporting frame —1— is disposed in a substantially horizontal plane and is

preferable recessed to form a lengthwise guideway —15— running parallel with the axis of the grindstone shaft —11— in proximity to the front edge of the grindstone 5 —10— for receiving and guiding a sliding carriage —16— which is held against upward displacement by dove-tail connections, shown more clearly in Fig. 3.

The adjacent sides of the section —8— 10 and carriage —16—, Fig. 3, are chambered longitudinally at —17— and —18—, respectively, for receiving a hollow cylinder —19— which is rigidly secured to the bottom of the section —8— parallel with the 15 guideway —15— for receiving a reciprocating piston —20—, Fig. 5, having oppositely projecting piston rods —21— extending through suitable glands in corresponding end heads —22— of the cylinder, said piston 20 being adapted to be operated in reverse directions by fluid pressure, as oil, through the medium of a power-driven pumping device, hereinafter described, and also serves to transmit similar motion to the carriage 25 —16—.

For this latter purpose, the carriage is provided with pendent abutments —23— and —24— engaging the outer ends of the piston rods —21—, (see Fig. 5), the abutment —23— being rigid or integral with the carriage, while the other abutment —24— is adjustable, it being pivoted at —25— to suitable lugs on the under side of the carriage and provided with a laterally projecting shoulder —26— registering with an adjusting screw —27— in said carriage for taking up any lost motion between the abutments and piston rods.

As shown in Fig. 5, the central portion of 40 the section —8— of the main supporting frame is provided with an upright pendent pump case —28— suitably secured to the under side thereof directly under the central portion of the cylinder —19— for receiving 45 a rotary valve —29— having an eccentric bore —30—, in which is mounted a rotary impeller —31— coaxial with the axis of the valve and, therefore, eccentric to the bore thereof, said impeller being provided with 50 one or more, in this instance four, radial blades —32— spring-pressed outwardly against the walls of the bore —30— by coil springs —33—, Fig. 7.

The valve —29— is fitted to turn freely 55 in the central bore, as —28—, of the pump case and is provided with a pair of ports —34— at diametrically opposite sides of the impeller, but mainly to one side of the center of the bore —30— for communication 60 with corresponding ports —35— in diametrically opposite sides of the pump case —28—.

These ports —35— communicate with upright passages —36— in the pump case 65 —28— and extend through the superposed

portions of the section —8— where they communicate with radial ports —37— in the adjacent side of the cylinder —19— at opposite ends of the piston —20— so that if the valve —29— is in the position shown in Fig. 7 and the impeller is rotated in the direction indicated by the arrow in the same figure, the circulating fluid, as oil, will be drawn from the right-hand end of the cylinder through the corresponding passage 70 —36— into the impeller chamber and then forced through the left-hand passage —36— into the cylinder —19— at the left-hand end of the piston —20—, thereby forcing said piston to the right (Fig. 5) and effecting a similar movement of the carriage —16— in the same direction, while on the other hand if the valve —29— is rotated a half revolution to reverse the position of its ports —34—, the movement of the piston 80 —20— and carriage will be correspondingly reversed.

The pump case —28— and cylinder —19— are secured, respectively, to the lower and upper faces of the intermediate portion 90 of the frame section —8— by bolts —38—, Figs. 6 and 7, and, therefore, become a rigid part of the frame, but separable for convenience of manufacture.

The upper and lower ends of the valve 95 —29— are closed by suitable plates or end heads —39— to prevent leakage of the pressure fluid and are preferably secured to said valve —29— to rotate therewith. The impeller —31— is preferably driven from the 100 grindstone shaft —11— through the medium of suitable connections, and for this purpose is secured to an upright shaft —40— which is journaled in the pump case —28— and is provided with a worm gear —41— 105 keyed thereto.

Meshing with the worm gear —41— is a worm —42— (Fig. 3) on a horizontal shaft —43— which is journaled in suitable bearings on the pump case —28— and frame section —8—, and is provided with a grooved pulley —44— connected by a belt —45— to a pulley —46— on the grindstone shaft —11— (see Fig. 4), thus rotating the impeller continuously as long as the grindstone is in operation.

Automatic reverse control.

A horizontal rock shaft —47— is journaled in the central portion of the frame 120 section —8— between the pump case —28— and cylinder —19—, and preferably in the same plane as and at right angles to the axis of the impeller shaft —40—, and is provided at its inner end with a double stop pawl or 125 escapement —48— so as to rock therewith for alternately forcing the opposite ends of the pawl into the path of a yielding abutment —49— which, in this instance, constitutes a part of the lever —50— eccentrically 130

pivoted at —51— to the top face of the upper disk or plate —39— of the rotary valve ring —29— so as to rotate with said ring, the lever —50— being also provided with a brake-shoe —52— for frictional engagement with the inner cylindrical walls of the pump case —28— when the abutment —49— encounters either end of the stop pawl —48—, as shown more clearly in Fig. 6.

10 The friction produced by the rotary impeller —31— and also that produced by the circulation of the oil tends to rotate the valve ring —29— and lever —50— thereon, but is prevented from such rotation by the 15 engagement of the abutment —49— with one end or the other of the stop pawl —48— and it, therefore, follows that if the holding end of the stop pawl is rocked from its holding position, the opposite end will be forced to 20 a similar holding position, thus permitting the rotation of the valve ring —29— and lever —50— through a substantially half revolution for reversing the position of the ports —34— relatively to the ports —35— 25 and thereby reversing the direction of flow of the fluid and effecting a corresponding reversal of movement of the piston —20— and carriage —16—.

The free end of the lever —50—, Fig. 6, 30 is spring-pressed forwardly in the direction of rotation by means of a spring —53— to release the brake-shoe —52— from frictional engagement with the inner walls of the pump case —28— as soon as either end 35 of the pawl —48— is withdrawn from holding engagement with the abutment —49—.

On the other hand, when the abutment —49— encounters either end of the pawl —48— at the end of each half revolution of 40 the valve ring —29—, it will automatically force the brake-shoe into frictional engagement with the inner wall of the pump case —28—, thereby aiding in stopping the further rotation of the valve ring —29— until 45 the pawl —48— is again shifted.

The rock shaft —47— extends forwardly through the front side of the frame section —8—, as shown in Figs. 3 and 8, and is provided with an upwardly projecting radial 50 arm —54— adapted to be operated by suitable devices on the front side of the carriage —16—.

As shown more clearly in Figs. 3 and 8, these devices consist of a pair of spaced bell- 55 crank levers —55— having their upper ends pivoted at —56— to a forwardly projecting portion —57— of the carriage —16— and their lower ends provided with pins or lugs —58— disposed at opposite sides of the upper end of the arm —54—, said levers being 60 adjustable about their pivots —56— by means of adjusting screws —59— for permitting the operation of the stop pawl —48— and consequent reversal of the valve ring —29— earlier or later in the movement

of the carriage in either direction, as may be desired.

It is now clear that the pins —58— not only control the direction of flow of the fluid from the impeller to the cylinder —19— for 70 operating the piston —20— and carriage —16— in reverse directions, but also determine the amount of movement of the carriage in either direction, such movement being preferably limited to a distance slightly 75 less than the face width of the grindstone so that the lens which is supported indirectly by the carriage will remain in contact with the grindstone in all positions of movement of the carriage.

80

Lens holding—and operating means therefor.

The carriage —16— is provided at its opposite ends with upwardly and rearwardly projecting arms —60— carrying at their upper ends pivotal screws —61—, Fig. 2, engaging and supporting the opposite ends of a forwardly and rearwardly oscillating frame —62— for receiving and supporting a lens-holder —63— and operating means 85 therefor, the frame —62— being hollow and fluid-tight to receive a quantity of oil or other lubricant for lubricating the various moving parts therein.

Secured to one end of the frame —62— 90 above its axis of movement is an extension —64— in which is journaled a shaft —65— to which rotary motion is transmitted from the grinder shaft —11— through the medium of the shaft —43— and suitable connections between the shafts —43— and —65—.

As illustrated more clearly in Figs. 1, 4 and 5, these connections consist of a worm —66— on the shaft —43— meshing with a 105 worm gear —67— on the lower end of an upwardly extending flexible shaft —68—, the upper end of which is provided with a spiral gear —69— meshing with a similar spiral gear —70— on the shaft —65—. 110

The lower end of the flexible shaft —68—, Fig. 4, is journaled in a yoke —71— which is pivotally hung upon the shaft —43—, the upper end of said shaft being journaled in a yoke —72— which is journaled upon an 115 eccentric portion of a rock shaft —73— having its ends journaled in a part of the extension —64— of the oscillating frame —62—, the rock shaft —73— being provided with a radially extending handle —75— by which 120 it may be rocked to shift the gear —69— into and out of mesh with the gear —70— for stopping and starting the lens-holder independently of the grindstone or reversing mechanism for the carriage —16—.

The outer end of the shaft —65— is provided with a hand-wheel —76— by which the shaft —65— and parts operated thereby may be adjusted in the initial setting up of the machine.

125

130

The lens-holder —63— comprises a pair of coaxial lens-clamping members operatively connected to suitable coaxial rotary spindles as —80—, Fig. 1, to rotate there-
5 with.

These spindles are journaled in suitable bearings in the lower portion of the oscillating frame —62— some distance below and parallel with the axes of the pivotal screws
10 —61— for said frame and also parallel with the axis of the main driving shaft —65—, each spindle being connected by a similar train of gears, not shown, to the opposite ends of a secondary driving shaft —82—,
15 the latter being journaled in the upper portion of the frame —62— parallel with the axes of the lens-holder —63— a predetermined distance to one side of the axis of the main driving shaft —65—, the gears being
20 so constructed and arranged as to drive both of the lens-holders in the same direction at one-half the speed of the secondary driving shaft —82—.

Suitable means is provided for transmitting rotary motion from the main driving shaft —65— to the secondary driving shaft —82— and causing the secondary shaft —82— and lens-holder driven thereby to revolve in the same direction as the driving
30 shaft, but at different speeds during each revolution so that all portions of the lens may be ground to the desired form at about the same time.

A lens pattern —89— is mounted coaxially
35 with the lens-holder —63— to rotate therewith against a back-rest —111— to determine the form of the lens which is being ground.

Means, including a bushing —101— and
40 an operating handle —102—, is provided for operating one of the parts of the lens-holder to clamp and release the lenses therein and therefrom.

Suitable means is also provided for automatically rocking the lower end of the frame —62— toward the grindstone to cause the lens to contact therewith, and for this purpose a lever —103— is pivoted at —104— to the outside of the upper portion of the shield
45 —4— and is provided with a downwardly projecting arm —105— connected by a link —106— to an arm —107— on the frame —62—, as shown more clearly in Figs. 1 and 2, said lever —103— being provided with a
50 forwardly and rearwardly extending guide —108— upon which is adjustably mounted a weight —109—, the latter being held in its adjusted position by a set screw —110—.

The periphery of the pattern —89— is
60 adapted to ride against a suitable back-rest —111— which is mounted in a suitable guide —112— on the carriage —16— and may be adjusted by means of a hand-piece —113—, said carriage being also provided with a
65 suitable truing device —114— capable of

being adjusted at will to keep the face of the grindstone smooth and true.

The use of the eccentric valve ring —29— in connection with an impeller, as —31—, for changing the direction of flow of the
70 fluid without changing the direction of rotation of the impeller is believed to be basically new not only in connection with grinding machines, but as a mechanical movement adapted for various purposes.

What I claim is:

1. In hydraulic power-transmission, the combination of a piston motor, an impeller for circulating fluid to and from the motor for operating the piston, a rotary valve actuated by the impeller for reversing the flow of fluid to the motor to reciprocate the piston, and means actuated by the motor for alternately and periodically stopping and releasing the valve.

2. In hydraulic power-transmission, the combination of a piston motor, an impeller for circulating fluid to and from the motor for operating the piston, a rotary valve actuated by the impeller for reversing the flow of fluid to the motor to reciprocate the piston, an abutment on the valve, a detent co-operating with said abutment to stop the valve, and means actuated by the motor for tripping the detent.

3. In hydraulic power-transmission, the combination of a piston motor, an impeller for circulating fluid to and from the motor for operating the piston, a rotary valve actuated by the impeller for reversing the flow of fluid to the motor to reciprocate the piston, an abutment on the valve, detents movable alternately into and out of the path of said abutment, and means actuated by the motor for periodically withdrawing one detent from and simultaneously forcing the other detent into said path.

4. In hydraulic power-transmission, the combination of a piston motor, an impeller for circulating fluid to and from the motor for operating the piston, a valve actuated by the impeller for reversing the direction of flow of the fluid, an escapement mechanism for periodically stopping and releasing the valve to produce said reverse flow and means actuated by said motor for operating the escapement.

5. In hydraulic power-transmission, the combination of a piston motor, an impeller for circulating fluid to and from the motor for operating the piston, a rotary valve actuated by the impeller for reversing the flow of fluid to the motor to reciprocate the piston, a carriage, means for transmitting motion from the motor to the carriage, and means actuated by the carriage for periodically stopping and releasing the valve.

6. In hydraulic power-transmission, the combination of a piston motor, an impeller for circulating fluid to and from the motor

for operating the piston, a rotary valve actuated by the impeller for reversing the flow of fluid to the motor to reciprocate the piston, an abutment on the valve, a detent 5 operating with said abutment to stop the valve, and means actuated by the carriage for tripping the detent.

7. In hydraulic power-transmission, the combination of a piston-motor, an impeller 10 for circulating fluid to and from the motor for operating the piston, a valve actuated by the impeller for reversing the direction of flow of the fluid, an escapement mechanism controlling the operation of the valve, a carriage actuated by the motor, and means 15 on the carriage for operating the escapement mechanism.

8. In combination with a fluid operated motor, a rotary impeller for circulating fluid 20 to and from the motor to operate said motor, a rotary valve controlling said circulation

and having means for reversing the flow of the fluid to and from the motor, an escapement controlling the operation of the valve, and means for controlling the operation of 25 the escapement.

9. In combination with a fluid-pressure-operated device, a rotary impeller for the fluid, a valve ring surrounding the impeller eccentric thereto and provided with ports in 30 opposite sides thereof, and means for shifting the ring circumferentially for reversing the position of its ports and thereby reversing the direction of flow of the fluid from the impeller to said device. 35

In witness whereof I have hereunto set my hand this 11th day of March, 1918.

ELI M. LONG.
